ALBERT HENRY SMITH, OF BIRMINGHAM, ENGLAND.

FEED MECHANISM FOR MACHINE-TOOLS.

1,057,097.

Specification of Letters Patent.

Patented Mar. 25, 1913.

Application filed October 25, 1912. Serial No. 727,717.

To all whom it may concern:

Be it known that I, ALBERT HENRY SMITH, subject of the King of Great Britain, residing at 155 St. Lukes road, Birmingham, in the county of Warwick, England, have invented a new and useful Feed Mechanism for Machine-Tools; and I do hereby declare the following to be a full, clear, and exact description of the same.

10 My invention comprises improvements in feed mechanism for machine tools more particularly of the kind which is known as bar-feed mechanism or feed collets as commonly employed upon capstan, and turret lathes 15 for intermittently feeding forward a metal rod from which a large number of articles are successively machined and cut off, and refers to that class of such feed mechanism in which radially disposed gripping members 20 are employed which grip and feed forward the rod when moving in the one direction and pass over same when moving in the other direction, the object of the present invention being to provide a gripping device 25 which may be readily adjusted for efficient use upon rods of widely differing diameters.

According to my invention I employ a series of radially disposed members which 30 present a chisel like point to the bar in one direction in combination with spring means for holding these radially disposed members in contact with the bar and a longitudinally moving inclined member which engages 35 with the outer ends of the radially disposed members for positively adjusting their effective gripping diameter.

Referring to the drawings:—Figure 1 is an elevation of a feed collet according to 40 this invention. Fig. 2 is an end view of same. Fig. 3 is a longitudinal section. Fig. 4 is a similar section with the parts adjusted to a different position. Fig. 5 illustrates the spring plunger in elevation and section. 45 Fig. 6 illustrates the gripping finger removed.

In carrying my invention into practice as illustrated upon the accompanying drawings the mechanism is carried by a sleeve 1 50 bored to pass a rod of the maximum size upon which the mechanism is to operate. The forward end of this sleeve is enlarged or flanged with two inclined surfaces 2, 3. Extending from the rear inclined surfaces 2 55 and disposed in a radial direction but inclining toward the front end of the sleeve

are three or more fingers 4 having hollow chisel points 5.

In the front inclined surface 3 I drill holes corresponding with and substantially 60 at right angles with the gripping fingers, these holes being tapped to receive spring plungers which may be in the form of a hollow screw 6 carrying a round nosed plunger 7 with a spiral spring 8 interposed 65 between these two parts. These plungers serve to hold the inclined gripping fingers solidly against their seatings 9, but when the bar is feeding forward or when a new bar is being inserted they allow the gripping fingers to lift, but obviously when the mechanism is feeding forward or if the bar seeks to move back the gripping fingers being already closely against their seating there will be no lost movement. The outer ends 70 of the gripping fingers will be practically flush with the rear inclined surface aforesaid and immediately behind this surface the sleeve is screwed to receive a collar 10, the forward end of which is bored taper 75 as 11 to substantially correspond with the rear inclined surface. This collar screwing up against the rear and outer ends of the gripping fingers which project beyond the rear inclined surface will obviously serve to 80 force the said fingers inwardly when the ring is rotated. A second and locking ring 85 12 screws upon the sleeve against the rear of the adjustment ring and serves to lock same in its adjusted position. It will be 90 obvious that when a bar as 13 is inserted between the fingers from the rear end of the mechanism the fingers may be forced outwardly to the full extent allowed by the adjustment ring, while by shifting the ring 95 endwise a very delicate adjustment may be obtained and as the gripping fingers work under the influence of the spring plungers it will be clear that they will efficiently operate upon stock bars of slightly differing 100 diameters without necessitating adjustment, while obviously the pressure of the spring plungers may be adjusted if so desired.

My improved feed mechanism may be employed either for holding the bar against 105 longitudinal movement when the feed control is moving backwardly or it may be itself employed for gripping the rod for feeding forward but two of the preferred devices are preferably employed in connection with capstan or turret lathes one for each purpose.

The invention is particularly applicable for use in connection with the intermittent feed described in my United States Patent No. 1019542 A. D. 1910 and the chucking mechanism described in United States Patent No. 952149 A. D. 1908.

What I claim then is:—

1. In a feed collet for machine tools, the combination of a sleeve like body; a plurality of radially disposed inclined gripping fingers presenting chisel points to grip the work rod and located in said body; a corresponding number of spring plungers engaging said fingers and serving to retain same in engagement with the work rod; and a longitudinally movable internally tapered adjusting member engaging the outer ends of the fingers and serving when moved longitudinally to adjust said fingers radially in order to vary the effective gripping diameter.

2. In a feed collet for machine tools, the combination of a sleeve like body; a plurality of radially disposed inclined gripping fingers adapted to grip the work rod and located in said body; means for retaining the fingers in engagement with the work rod; and a movable adjusting member adapted to engage the outer ends of the fingers and simultaneously move the fingers to vary the effective gripping diameters.

3. In a feed collet for machine tools, the combination of a sleeve like body having a series of radially disposed inclined openings; a plurality of similarly radially disposed inclined gripping fingers located one in each opening and presenting chisel points to grip the work rod; a corresponding number of plunger carriers screwing into said body, one being adjacent to each finger; a spring plunger located in each of said carriers engaging said fingers and serving to retain them in engagement with the work rod; and a longitudinally movable internally tapered adjusting member engaging the outer ends of the fingers and serving when moved longitudinally to adjust said

fingers radially in order to vary the effective gripping diameter.

4. In a feed collet for machine tools, the combination of a sleeve like body externally screwed; a plurality of radially disposed inclined gripping fingers presenting chisel points to grip the work rod and located in said body; a corresponding number of spring plungers engaging said fingers and serving to retain same in engagement with the work rod; an internally tapered ring screwing upon said body engaging the outer ends of the fingers and serving when rotated and thus moved longitudinally to adjust said fingers radially in order to vary the effective gripping diameter; and a locking ring for securing the tapered ring in its adjusted position.

5. In a feed collet for machine tools, the combination of a sleeve like body; a plurality of radially disposed inclined gripping fingers presenting chisel points to grip the work rod and located in said body; means for retaining said fingers in engagement with the work rod; and a longitudinally movable internally tapered adjusting member engaging the outer ends of the fingers and serving when moved longitudinally to adjust said fingers radially in order to vary the effective gripping diameter.

6. In a feed collet for machine tools, the combination of a sleeve like body; a plurality of radially disposed gripping fingers adapted to grip the work rod and located in said body; means for retaining the fingers in engagement with the work rod; and a movable adjusting member adapted to engage the outer ends of the fingers and simultaneously move the fingers to vary the effective gripping diameters.

In testimony whereof, I have signed my name to this specification in the presence of two subscribing witnesses.

ALBERT HENRY SMITH.
